UNITED STATES PATENT OFFICE.

FREDERICK J. WILKES, OF PHILADELPHIA, PENNSYLVANIA, ASSIGNOR, BY DIRECT AND MESNE ASSIGNMENTS, TO THE AMERICAN SEALING MACHINE COMPANY, OF ALEXANDRIA, VIRGINIA.

MACHINE FOR MOISTENING AND SEALING ENVELOPS.

SPECIFICATION forming part of Letters Patent No. 651,090, dated June 5, 1900.

Application filed June 14, 1899. Serial No. 720,535. (No model.)

To all whom it may concern:

Be it known that I, FREDERICK J. WILKES, of Philadelphia, in the county of Philadelphia and State of Pennsylvania, have invented certain new and useful Improvements in Machines for Moistening and Sealing Envelops; and I do hereby declare the following to be a full, clear, and exact description of the invention, such as will enable others skilled in the art to which it appertains to make and use the same.

My invention relates to an improvement in machines for moistening and sealing envelops, one object of the invention being to improve and simplify various features of construction of envelop-sealing machines and to produce a machine of the class specified which shall be effectual and accurate in the performance of its functions.

20 A further object is to so construct and arrange moistening devices that the moisture will be applied in such manner and quantity as to prevent the outer face of the flap of the envelop becoming wet or dampened.

25 A further object is to so construct the apparatus that envelops of any size can be effectually sealed without necessity for adjustment of any part to accommodate envelops of different sizes.

30 With these objects in view the invention consists in certain novel features of construction and combinations and arrangements of parts, as hereinafter set forth, and pointed out in the claims.

35 In the accompanying drawings, Figure 1 is a plan view illustrating a machine embodying my improvements. Fig. 2 is a longitudinal sectional view. Fig. 3 is a transverse sectional view. Figs. 4 and 5 are views of

40 details.

A represents a suitable base, preferably of metal, upon which a water-reservoir B is located, and over said reservoir a platform C is secured for the reception of envelops to be sealed, one side of the wall of the reservoir being made to project above the plane of the platform to act as a guide 1 for the envelops. To provide simple means for supplying the reservoir with water a funnel 2 may be employed, said funnel being supported by or

made integral with a short bent pipe 3, adapted to communicate with a hole in one wall of the reservoir.

The platform C is provided on its under face with divergent guides 4 of a length about 55 equal to the width of the reservoir, and these guides receive and support from the under side of the platform a wedge-shaped moistener D, which is of sufficient length to moisten the flap of the largest envelop in commercial use, but which will with equal efficiency moisten the flap of a very small envelop.

The moistener comprises a flat tapering plate 5 and a convex tapering plate 6, secured at their edges so as to form a compartment between them, and within this compartment one end of a wick 7, of suitable absorbent material, is secured, the other end of said wick being immersed in the water in the 70 reservoir. The convex plate 6 is provided with a number of perforations 8, through which water conducted to the moistener by capillary attraction can escape. The water thus discharged by the wick through the openings 8 in the plate 6 will be received by a covering 9, of felt or similar material, secured over the plate 6, and in this manner the felt covering will be kept sufficiently saturated to effectually moisten the mucilage on the 80 flap of an envelop, passing under the moistener without unduly wetting the flap or permitting water to find its way on the outer face thereof. In order to insure an adequate amount of water to the moistener, the end of 85 the wick which is immersed in the water in the reservoir is enlarged and split.

A plate 10 is disposed over the reservoir directly under the platform C and is made with a transverse groove or depression 11, 90 into which the moistener D projects. The forward end of the plate 10 preferably projects somewhat beyond the reservoir, and that portion of said plate from the inner end thereof to the groove or depression 11 is 95 curved downwardly in such manner that its left-hand edge will be lower than the right-hand edge to form a folder for the flaps of the envelops.

From the construction and arrangement of 100

parts above described it will be seen that when an envelop is presented to the machine with the flap down the flap will engage the curved portion of the plate 10 and be thus folded or pressed up toward the under face of the platform. As the envelop is forced forward the gummed face of the flap will pass under the moistener, by which it will be bent into the groove or depression 11 in the plate 10, and thus intimate contact between the flap and the moisture and consequent moistening of the flap will be insured.

After passing the moistener the envelop will be delivered to sealing-rollers 12 13, between which it will pass and by means of which the flap will be tightly pressed against the body of the envelop and sealed.

The lower sealing-roller 12 is at its respective ends in fixed bearings in standards 14 15. The standard 14 at the right-hand side of the machine is much higher than the standard 15 at the other side of the machine, and to the top of said standard 14 a cross-head 16 is secured. The cross-head 16 is provided at its free end with a depending arm 17, in line with the short standard 15 and terminating a short distance above the latter, thus having an opening 18, through which the body of a wide envelop can pass.

The standard 14 and the depending arm 17 are made with vertical elongated slots 19 for the reception of journal-boxes 20 for the upper roller 13. The boxes 20 are movably disposed in the slots 19 and are preferably provided in their diametrically opposite walls with grooves or depressions to receive similarly-shaped enlargements 22 on the walls of the slots 19 for the purpose of preventing lateral displacement of said boxes. The journals of the upper roller have bearings in the lower ends of the boxes 20, and said upper roller normally rests upon the lower roller. The journal-boxes are made hollow or provided with sockets 24, in which coiled springs 25 are disposed, and the sockets may be made to also contain lubricant, which can be fed to the journals of the upper roller through small ducts 26. A cap or head 27 rests upon each coiled spring for the reception of the lower end of thumb-screws passing downwardly through the cross-head 16. By these devices the tension of the springs 25 and the pressure exerted by the rollers on the envelop passing between them can be easily, quickly, and effectually regulated according to thickness of

the contents of envelops to be sealed. The roller 12 13 may be made of rubber or other yielding material.

After passing between the sealing-rollers 12 13 the envelops may, if desired, be passed between another pair of rollers 28, and between the pairs of rollers a platform 29 is preferably located.

Having fully described my invention, what I claim as new, and desire to secure by Letters 65 Patent, is—

1. In an envelop-sealing machine, the combination of a platform, a plate below the platform having a groove or depression, a moistener attached to the under face of the platform transverse to the path of the envelop and depending therefrom into the groove or depression in the plate whereby when the flap of an envelop is passed under said moistener, it will enter the groove or depression in the plate and be bent to partially embrace the moistener. 70

2. In an envelop-sealing machine, the combination of a platform, a rigid moistener depending from the under face thereof transverse to the path of the envelop, and a folder under the platform and having a depression into which said rigid moistener projects to deflect the flap of an envelop and cause it to partially embrace said moistener. 80

3. In an envelop-sealing machine, the combination of a platform and a vertical envelop-guide at one side thereof, a moistener depending from the under face of said platform transverse to the path of the envelop, a plate 90 under the platform having a depression into which said moistener projects, the portion of the plate between said depression and the inner end of the plate being curved downwardly in a diagonal direction to form a folder. 95

4. In an envelop-sealing machine, the combination with a support having guides, of a moistener-mounted in said guides, said moistener comprising two plates one of which is made with an opening, a wick projecting into the space between said plates, and absorbent material disposed over the plate having the opening. 100

In testimony whereof I have signed this specification in the presence of two subscribing witnesses.

FREDERICK J. WILKES.
